CLAIM

The ornamental design for a fishing rod holder, as shown and described.

DESCRIPTION

FIG. 1 is a top, rear, and right side perspective view of a fishing rod holder showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a bottom plan view thereof;

FIG. 7 is a rear elevational view thereof; and,

FIG. 8 is a top, rear, and right side perspective view of a second embodiment, the only difference being that the article is a mirror image of that shown in FIG. 1.

FIG. 1

FIG. 3

FIG. 7

FIG. 4

FIG. 2

FIG. 5

FIG. 8

FIG. 6
